NEWSPAPER VENDING MACHINE

Jack S. Chalabian, Gardena, Calif., assignor to K-Jack
Engineering Company, Inc., Gardena, Calif.

Continuation of design applications Ser. No. 182,931 and
Ser. No. 182,932, both Sept. 22, 1971. This application
Feb. 23, 1973, Ser. No. 335,258

Term of patent 14 years

Int. Cl. D20—01

U.S. Cl. D52—3 R

FIG. 1 is a front perspective view of a newspaper vending machine showing my new design;

FIG. 2 is a right side elevational view thereof;

FIG. 3 is a front elevational view thereof;

FIG. 4 is a left side elevational view thereof;

FIG. 5 is a front perspective view of a newspaper vending machine showing another embodiment of my new design;

FIG. 6 is a right side elevational view thereof;

FIG. 7 is a front elevational view thereof; and

FIG. 8 is a left side elevational view thereof.

This application is a continuation application of my prior filed applications Ser. No. 182,931, filed Sept. 22, 1971 and Ser. No. 182,932, filed Sept. 22, 1971.

I claim:

The ornamental designs for newspaper vending machine, substantially as shown and described.
